COOLED ELECTRON DISCHARGE DEVICE

Application filed August 13, 1927. Serial No. 212,788.

My invention relates to radio tubes and particularly to tubes of large power in which the anodes comprise metallic portions of the walls of the tubes.

5 An object of my invention is to provide means for supporting a water jacket upon the anode of a high power electron discharge tube.

10 Another object of my invention is to provide means for detachably mounting the water jacket upon the anode of an electron discharge tube of high power.

15 Another object of my invention is to provide a water-tight connection for the water jacket to anodes of the character above described, without the necessity of welding, brazing or otherwise heating the anode to effect the attachment of the water jacket.

20 A further object of my invention is to provide a single means for supporting an electrostatic shield for the seal between a metallic anode and the wall portion inside an electron discharge tube, and for supporting the water jacket outside the discharge tube.

25 Other objects of my invention will become apparent upon reading the following specification taken in connection with the accompanying drawings, wherein:

30 Figure 1 is a longitudinal section of a radio tube embodying one form of my invention, and

Fig. 2 is a longitudinal section of a radio tube embodying a different form of my invention.

35 It has been common in the art of radio tubes adapted for producing considerable power outputs to make the anode in the form of a metallic shell constituting the wall at one end of the tube. The anode is then in

40 the form of a thin-walled metallic cup which is sealed to the glass wall constituting the remainder of the container by a ring-shaped seal. It has also been customary to surround this cup-shaped anode by a jacket through 45 which water circulates to efficiently carry away the heat generated in the anode during the operation of the tube.

Since such tubes of a large power ordinarily have relatively high potentials impressed between their electrodes, electro-

static fields of considerable intensity are set up in the neighborhood of the tube walls. The anodes are ordinarily sealed to the glass wall at one end and terminate in a relatively sharp edge, and these electric fields have a tendency to concentrate in the seal itself and frequently produce such high electric stresses as to cause rupture or overheating of the glass at that point. I have, therefore, arranged to insert directly inside the seal a 55 metallic extension of the anode by means of which the concentration of the electric field at the seals is avoided.

In order to provide an anode which shall be efficiently cooled by the surrounding water 60 jacket, it is customary to make the metallic wall portion above described as thin as is consistent with the ability to withstand the pressures of the surrounding atmosphere. A convenient way to make such anodes is to 65 draw them as a thin-walled copper cup in a die-press. Such process does not adapt itself to the formation of suitable supporting collars of the size and strength necessary for 70 attachment of the water jacket. It would, of course, be possible to braze or weld a suitable supporting collar to the outside of the anode, but if this were done before the tube were 75 exhausted, the interior of the anode would become oxidized. Such oxide cannot be left on the anode permanently, since it occludes gases 80 which it is almost impossible to completely remove by any known method of tube exhaust. These would gradually seep out of the oxidized layer after the tube was sealed off from the pumps and quickly cause the 85 vacuum to deteriorate to such an extent that the tube would be ruined for practical purposes.

Furthermore, such a collar would have to be located very close to the end of the anode which is sealed to the glass container and would make the forming of the seal thereto by the glass blower difficult or impossible.

Such an extension of the anode in close proximity to the seal, as has been described above as necessary to shield the latter from electrostatic fields, would also make great difficulties for the glass blower in forming the seal. It would likewise be oxidized by the 100

heat of the glass blower's fires and the removal of this oxide would present considerable difficulty. As previously stated, any such oxide must be removed before the tube 5 could be properly exhausted.

For the foregoing reasons, it is desirable that the above-mentioned support-collar and shield extension of the anode shall not be integral parts thereof, which must have been 10 attached previous to the time that the anode is sealed to the glass container. I have, therefore, devised a form of anode which permits the attachment both of a shielding-extension inside the tube and of a support collar 15 outside the tube, after the tube has been sealed to the glass portion of the tube.

The method which I have devised comprises the formation of a groove in the form 20 of a screw-thread in the metallic wall of the anode and the provision of threaded portions on both the support collar and the internal shield which engage this threaded groove and permit these elements to be placed in position and removed at will, after the anode 25 has been sealed to the container.

A convenient way of producing this groove in the anode is that of rolling it in the thin metal wall. This process naturally results 30 in the production of a screw-thread groove on the exterior of the anode and it is possible to utilize this external thread to fasten in place a water jacket such as is common for cooling anodes in power tubes of this type.

Referring to Fig. 1 of the drawings, the 35 power tube embodying my invention comprises a vitreous container 1 having at its upper end a reentrant neck 2 supporting a press 3 at which are sealed cathode heating leads 4 of an ordinary type. These leads and 40 a support stem 5 support a cathode filament 6 of a well-known type. Surrounding the press 3 is a glass neck 7 upon the exterior of which is clamped a collar 8 which supports rods 9 to form a frame work for a control 45 electrode 10 of the conventional grid type.

The anode for my radio tube comprises a cup-like metallic cylinder 11 which is sealed to the vitreous envelope 1 at the ring seal 12.

If the electrodes so far mentioned constituted 50 the entire tube structure, very considerable electric stresses would be produced in the neighborhood of the seal 12 when the tube was in use. Since these electric stresses are alternating, they produce considerable dielectric losses in the glass and thus tend to overheat it. In consequence of this heating and 55 of the electric stresses themselves, puncture of the glass at the seal would be very likely to occur.

To avoid these difficulties from concentration 60 of the electric field at the seal 12, I provide a cylindrical shield 13 which forms an extension of the anode 11 and eliminates electric stresses from the seal 12 for reasons 65 which will be readily apparent from mere in-

spection of the drawings. Moreover, this shield reduces electric stresses in the glass walls generally due to the potential difference between the anode and the grid.

However, if the shield 13 were made integral 70 with the anode 11, great difficulty would be found by the glass blowers in making the ring shaped seal 12 so close to this metallic shield. Furthermore, the shield 13 would be badly oxidized by the glass blower's flames 75 and would, in consequence, absorb considerable quantities of gas which would render a sufficient evacuation of the container difficult or impossible.

Accordingly, I have arranged the shield 13 80 to be detachable from the main anode 11 so that the latter may be sealed into the glass portion of the envelope before the member 13 is put in position. In constructing the tube, the glass member 1 is first sealed to the 85 anode 11, the upper end of member 1 being left open. A groove 14 in the form of a screw-thread is provided in the wall of anode 11. It may readily be formed by rolling it in the main metallic wall at the time the 90 anode is made. The shield member 13 is in the form of a thin tube and has a corresponding screw-thread rolled in it. The seal 12 having been completed and the anode thoroughly cleaned in a manner familiar in the 95 art, the member 13 is screwed into position in the anode 11 from the open upper end of the member 1. The neck 2 and press 3, on which the electrodes 6 and 10 have already 100 been assembled in a manner well known in the art, is next inserted through the open end of the tube 1 and sealed into place. The grid-lead 15 is next sealed in place through the tubulation 16.

The collar 17 for supporting the water 105 jacket may be screwed onto the anode at any time after the completion of the tube. Because of the yielding quality of copper metal, and of the thinness of the anode wall, this screw-thread 14 readily conforms to and 110 makes a relatively tight fit with the collar 17. However, to make certain that the joint between the two is water-tight the portion of the anode in which the thread is rolled may be made slightly larger in diameter than the 115 main wall of the anode thus providing a shoulder against which a packing 18 of asbestos or other suitable material may be squeezed when collar 17 is secured into place.

In the modification shown in Fig. 1, the 120 collar 17 is provided with a second collar 19 which is mounted on, and in engagement with a groove in collar 17, so that it can turn readily about the latter. The collar 19 may conveniently be made in two parts to admit 125 its ready mounting as just described. The lower face of the collar 17 is machined to a true surface adapted to engage a suitable gasket. The water-jacket proper 21 has an annular surface on its upper end adapted to 130

engage the annular surface of the collar 17. A suitable gasket 20 of lead or other material may be provided between the two annular surfaces to assure that their fit is a water-tight one. Upon the outside of the upper end of the water jacket 21 is cut a screw thread 22 and a cap 23 with a thread adapted to engage thread 22 is arranged with a bearing on the upper surface of the collar 19.

10 After the water jacket 21 is placed in position, the cap 23 is screwed down, drawing the water jacket tightly against the gasket aforesaid, producing a water-tight joint at the upper end of the water jacket. The freedom 15 of collar 19 to turn on collar 17 insures that no torsional stress will be applied to the thin-walled anode 11 in screwing cap 23 onto threaded portion 22.

The water jacket 21 is provided with suitable inlet and outlet connections for the cooling water. The construction of these is so well known as not to require detailed explanation.

Referring to the modification shown in Fig. 25 2, this differs from that shown in Fig. 1 in the detail of the method of attaching the water jacket proper to the collar. As shown in the drawings, the water jacket 25 may be of drawn metal having an annular surface on its upper end 26 adapted to cooperate with a similar annular surface on the support collar 27. A suitable gasket may be provided to render this joint water-tight, the pressure being provided by a ring of nuts 30 and bolts 35 31 around the cooperating edges. The ease with which the junction between the support collar 27 and the threaded groove of the anode 11 can be made water-tight is such that the water jacket may be removed from the 40 tube by merely unscrewing the latter from the inside of the collar 27. The structure shown in Fig. 2 has the advantage that practically the entire length of the anode is subjected to water-cooling.

45 It is, therefore, apparent that I have devised a convenient method for mounting the water jacket on the metallic anode of a high power radio tube and one which permits the easy exhaust of the tube and does not interfere with the glass blower's work of sealing the anode to the glass container. The same means is further used to support the electrostatic shield inside the tube, which prevents injury of the glass in the neighborhood 50 of the seal from electrostatic stresses incident to the operation of the tube. To support a shield for the seal of a power tube by this method is not my invention, but is claimed in copending application of Mourtseff and Deak, Serial No. 188,420, as 55 assigned to the Westinghouse Electric & Manufacturing Company.

60 While I have described my invention in connection with the particular embodiment here illustrated, it will be evident to those

skilled in the art that many departures from the proposed structure and process of construction which I have described may be made without departing from the principles of my invention. I, accordingly, desire that the 70 terms of the claims shall be given their broadest reasonable significance excepting so far as limitations are expressly made or are imposed by the prior art.

I claim as my invention:

75 1. An electrical discharge device comprising a vacuum-tight container, a cathode within said container, a portion of said container constituting the anode of said device and having threads consisting of undulations in 80 said portion, a collar having an annular face on one side thereof, and adapted to engage said threaded portion, a split ring rotatably supported on said collar, a water-jacket having an annular face adapted for water-tight engagement with said first annular face, and a screw cap adapted to engage said split ring and said water jacket, to press said two annular faces together.

85 2. An electrical discharge device comprising a vacuum-tight container, a portion of the wall of said container being simultaneously threaded on both sides constituting the anode of said device, an electrode in said container, a metallic member inside said container in 90 engagement with said threaded portion and a collar external to said container adapted to engage said threaded portion.

95 3. An electrical discharge device comprising a vacuum-tight container, a portion of the wall of said container being simultaneously threaded on both sides constituting the anode of said device, an electrode in said container, a metallic member inside said container in 100 engagement with said threaded portion, a collar adapted to externally engage said threaded portion and a water jacket supported by said collar.

105 4. An electrical discharge device comprising a vacuum-tight container having a metallic wall portion, a portion on said wall being simultaneously threaded on both sides, constituting the anode of said device, an electrode in said container, a metallic member inside said container in 110 engagement with said threaded portion, a collar in external engagement with said threaded portion and having an annular face on one side thereof, a second collar rotatably supported on said first collar, a water jacket having an annular face adapted for water-tight engagement with said first annular face and a screw cap adapted to engage said second collar and said water jacket to press the two said annular faces together.

115 5. An electrical-discharge device comprising a vacuum-tight container, part of the wall of said container constituting the anode of said device and having portions bent to form threads, said bent portions forming threads both inside and outside said con-

tainer, an electrode in said container, a metallic member inside said container in screw-threaded engagement with said bent portions, and a collar external to said container and in screw-threaded engagement with said bent portions.

6. An electrical discharge device comprising a vacuum-tight container, part of the wall of said container constituting the anode of said device having portions bent to form threads, said bent portions forming threads both inside and outside said container, an electrode in said container, a metallic member inside said container in screw-threaded engagement with said bent portions, said threads outside said container being adapted to make threaded engagement with a collar supporting a water jacket for cooling said anode.

20 In testimony whereof, I have hereunto subscribed my name this 3rd day of August 1927.

LEE HALL BENSON.
